DESIGN FOR A SHOWER HEAD

Harold A. Freeman, Akron, Ohio

Application July 7, 1939, Serial No. 85,883

Term of patent 7 years

To all whom it may concern:

Be it known that I, Harold A. Freeman, a citizen of the United States, residing at Akron, in the county of Summit and State of Ohio, have invented a new, original, and ornamental Design for Shower Heads, of which the following is a specification, reference being had to the accompanying drawing, forming part thereof.

I claim:

The ornamental design for a shower head, as shown.

HAROLD A. FREEMAN.
